UNITED STATES PATENT OFFICE.

JOHN W. BARGER, OF DANVILLE, ILLINOIS.

COLLAR-BUTTON.

1,315,902.

Specification of Letters Patent.

Patented Sept. 9, 1919.

Application filed June 6, 1919. Serial No. 302,290.

To all whom it may concern:

Be it known that I, JOHN W. BARGER, a citizen of the United States, and a resident of Danville, in the county of Vermilion and 5 State of Illinois, have made certain new and useful Improvements in Collar-Buttons, of which the following is a specification.

This invention is an improvement in collar buttons, and has for its object to provide 10 a construction to facilitate the insertion of the head of the button in the button-hole of a collar, and of a neck band. In doing this I form the head in a circular disk-like shape, brought approximately to an edge at its periphery, thus relieving the necessity of 15 spreading the hole to any considerable extent when inserting the button, and also reducing the thickness of the head of the collar-button to such an extent as to greatly 20 reduce the friction in slipping the neck-tie along the button head.

The invention consists in certain novel 25 constructions, as will be hereinafter more fully described and pointed out in the ap- pended claim.

In the drawing:—

Figure 1 is an end view, and,

Fig. 2 is a side view embodying my inven- 30 tion.

This button is shown enlarged many times for purposes of illustration.

The button has a base A, a shank B, and a head C. The base A and the shank B may be of ordinary construction and they may be 35 produced in any of the ordinary ways practised in the making of buttons of this class.

The head C is quite thin and is brought at its periphery practically to a knife edge, and is made very thin, so that its insertion through the button-hole of a neck band and 40 through the button-hole or holes in a collar, is rendered very easy, as it does not involve any considerable spreading of the button-hole in effecting such insertion.

It will also be noticed that the neck-tie 45 may readily slide across the head of the button, especially when the latter is used at the back of the collar, this resulting from the thin knife-like peripheral edge and the flat form of the button head, which causes the 50 latter to enter button-holes with the greatest ease.

Manifestly, in the use of the invention the shank may be made of different lengths to accommodate different thicknesses of folds 55 of collar and collar bands.

The construction is simple, easily operated, and effectively serves the purpose for which it is designed.

The head of the button is circular, and its 60 edge is uniform and thin and knife-like throughout, so that it readily enters the button-hole at any point in its periphery.

I claim:—

A collar button having a shank and a head 65 approximately circular in outline and lying in a plane approximately at a right angle to the axis of the shank with its peripheral edge throughout thin and knife-like, as and for the purposes set forth.

JOHN W. BARGER.
